UNITED STATES PATENT OFFICE.

ALEXANDER L. FOX, OF EAST ST. LOUIS, ILLINOIS, ASSIGNOR, BY MESNE ASSIGNMENTS, TO T. C. WHITE ELECTRICAL SUPPLY COMPANY, A CORPORATION OF MISSOURI.

WIRE-HANGER.

1,243,057.

Specification of Letters Patent. Patented Oct. 16, 1917.

Original application filed November 19, 1913, Serial No. 801,799. Divided and this application filed December 7, 1915. Serial No. 65,470.

To all whom it may concern:

Be it known that I, ALEXANDER L. Fox, a citizen of the United States, residing at the city of East St. Louis, county of St. Clair, 5 and State of Illinois, have invented a new and useful Wire-Hanger, of which the following is a specification.

This invention relates to improvements in wire hangers, and is a division of my application, Serial No. 801,799, filed November 19, 1913.

An object of the invention is to provide an improved wire hanger comprising a body composed preferably of insulation material, 15 such as porcelain, provided with an axial hole therethrough and with a central polygonal recess in its upper side, in combination with a releasable binding device extending through the hole and engaging with the wire 20 support and provided with a polygonal head or enlargement upon its upper end adapted to engage within the polygonal recess in the body, whereby said device will be locked and prevented from working loose when the 25 device is assembled, a portion of the polygonal enlargement or head extending above the upper side of the body and constituting an engageable portion whereby the body and the binding device may be detached or 30 removed without defacement of either. In this connection it will be understood that the body is rigidly or firmly clamped between the supporting wire and the connecting yoke, so that the body cannot readily be turned 35 either for the purpose of releasing or mounting it without the use of the polygonal enlargement or head on the binding device.

With the foregoing general object and other specific objects in view, I have produced a preferred embodiment of the invention which I have illustrated in the accompanying drawings, in which—

Figure 1 is a plan view of the hanger and the coöperating parts assembled in connection therewith.

Fig. 2 is a side elevation thereof.

Fig. 3 is a vertical section through the body illustrating the binding device passing therethrough.

50 The line wire 1 is supported by the usual ear or supporting member 2 having an upwardly extending portion 3 intermediate of its ends, which is provided with a threaded recess 4. These parts are of the usual con-

struction and it is in combination with them 55 that my present invention is to be employed.

The insulating body 5 in the embodiment illustrated is cylindrical and is clamped between and supported by a transverse wire 6 and a clamping yoke 7. The wire 6 extends 60 across one side of the body and the yoke 7 bears against the opposite side of the body and is provided with hooks 8 which engage with the wire 6, thus firmly or rigidly clamping the body 5 between the yoke and the 65 wire, so that when the device is mounted for use the body will be positively retained in position and cannot turn or work loose.

The wire 6 and the yoke 7 engage in a circumferential groove in the body 5 so 70 that the parts are thus retained in proper relative position when they are mounted.

The body 5 is provided with a central hole 9 and in the upper side of the body a polygonal recess 10 is formed. The hole 9 75 opens into the center of the recess and receives the binding device 11 which passes through the hole and engages in the threaded recess 4. The binding device 11 is preferably of smaller diameter than the hole 9 80 so that said device will be free to revolve with respect to the body 5 during the initial operation of the device in securing the parts together. The upper end of the binding device 11 is provided with a polygonal head 85 or enlargement 12 adapted to seat within the recess 10, so as to interlock the binding device with the body 5 and thereby prevent the binding device from turning or working 90 loose.

When the head or enlargement 12 is seated against the bottom wall of the recess 10 the upper portion of said head or enlargement projects or extends above the upper surface of the body 5, thus constituting an engageable portion with which a wrench or other tool or implement may be engaged to tighten or to release the binding device. Obviously, when the head or enlargement 12 is seated within the recess 10 the binding device can 100 not turn with respect to the body 5, but both must turn together. Thus, since the body 5 is firmly or rigidly clamped between the wire 6 and the yoke 7 and is thereby prevented from turning except as the result of 105 the application of relatively great force, it is manifestly impossible for the parts to become loose. However, should it be desired

to release the parts, this may be done by engaging the wrench or like with the polygonal head or enlargement 12 and applying sufficient force to overcome the gripping and clamping power of the wire 6 and yoke 7. Since the body 5 cannot revolve because of its rigid engagement between the wire and the yoke, it is plainly impossible for any of the parts to become loose.

16 What I claim and desire to secure by Letters Patent of the United States, is:

1. A wire hanger comprising a body having a hole therethrough and having a polygonal recess in its upper side, and a support port normally preventing said body from turning, in combination with a wire support at the lower side of said body, a binding device passing through said hole and having threaded engagement with said wire support, and a polygonal enlargement on said device seated in said recess and extending above the upper side of said body, and constituting an engageable part whereby said binding device and said body may be forcibly turned and disconnected from the wire support while the wire support remains in connection with the wire supported thereby.
2. A wire hanger comprising a body having a hole therethrough and having a polygonal recess in its upper side, and means for supporting and normally holding said body from turning, in combination with a support for the line wire below said body, a binding device passing through said hole and having threaded engagement with said support, and an engageable polygonal portion on said device seated in said polygonal recess and extending above said body whereby said portion may be engaged and said binding device and said body forcibly turned to un-

screw said binding device from the line wire support.

3. A wire hanger comprising a body having a hole therethrough and having a polygonal recess in its upper side, and a support normally holding said body from turning, in combination with a wire support below said body, a binding device passing through said hole and being screwed into said wire support, and a polygonal enlargement on said binding device seated in said recess and locking said device and said body together, said enlargement having an engageable portion extending above the upper surface of said body, whereby said binding device and said body may be forcibly turned to unscrew said binding device from the wire support while the latter remains in connection with the wire supported thereby.

4. A wire hanger comprising a body having a hole therethrough, and means for supporting said body and normally preventing it from turning, in combination with a wire support below said body, a device binding said wire support in connection with said body, and means constituting a lock between said device and said body and also constituting an engageable portion for forcibly turning said body, whereby said device and said body may be disconnected from the wire support while the latter remains in connection with the wire supported thereby.

In witness whereof, I have signed this specification in the presence of two subscribing witnesses.

ALEXANDER L. FOX.
